UNITED STATES PATENT OFFICE.

GEORGE SEIBERT, JR., OF ALBIA, IOWA.

SELF-CLEANING SPARK PLUG.

Application filed July 21, 1922. Serial No. 576,448.

To all whom it may concern:

Be it known that I, GEORGE SEIBERT, Jr., a citizen of the United States, residing at Albia, in the county of Monroe and State 5 of Iowa, have invented certain new and useful Improvements in Self-Cleaning Spark Plugs, of which the following is a specification.

This invention relates to self-cleaning 10 spark plugs for internal combustion engines and has for its object to provide a device of this character which will be simple in construction, comparatively inexpensive to manufacture and more efficient in operation 15 than those which have been heretofore proposed.

A further object of the invention is to provide a spark plug which will quickly and 20 efficiently remove any carbon or other deposits which may accumulate adjacent the spark gap, thereby preventing the short circuiting of the plug and the mis-firing of the cylinder.

A still further object of the invention is 25 to provide a spark plug in which the cleaning feature may be either automatically or manually actuated, or which, if desired, may be rendered inoperative at will, under which conditions the plug may be used in the same 30 manner as the ordinary spark plug.

With the above and other objects in view 35 which will appear as the description proceeds, the invention consists in the novel details of construction and combinations of parts more fully hereinafter disclosed and particularly pointed out in the appended claims.

In the accompanying drawings forming 40 a part of this specification in which like numerals designate like parts in all the views:

Figure 1 is a central, vertical, sectional view partly in elevation of one form of spark plug, made in accordance with the present invention;

Fig. 2 is a horizontal sectional view taken 45 approximately on the plane indicated by the line 2-2 of Fig. 1;

Fig. 3 is a fragmentary, central, vertical, sectional view of a slightly modified form 50 of the invention;

Fig. 4 is a diagrammatic elevational view 55 illustrating the manner of manually controlling the cleaning feature; and,

Fig. 5 is a horizontal sectional view taken 60 approximately on the plane indicated by the line 5-5 of Fig. 4.

Referring more especially to Figs. 1 and 2, the numeral 10 indicates the metallic shell or casing of the plug, the lower end of which is preferably threaded as at 11, to engage 60 the usual threads in the cylinder walls of the engine. The upper end of the said shell 10 is preferably enlarged, as at 12, and is recessed and threaded, as at 13, to receive the lower portion 14 of a porcelain or other 65 suitable insulating member 15, which is normally retained in place by means of the threaded bushing 16, engaging the shoulder or flange 17, with which the said lower portion 14 is provided.

The said shell is provided with a central bore 18 extending entirely through the same, the upper portion of the said bore being enlarged as at 19, and the two portions being connected by an inclined surface 20, 70 serving as a valve seat, as will presently appear.

The insulating member 15 is provided with an axial bore 21 in which is slidably mounted the central electrode 22 which extends 80 entirely through the said member 15 and axially of the bores 18 and 19 to a point below the lower end of the shell or casing 10. The said lower end of the casing is provided with the usual curved electrode 85 23 which is suitably spaced from the electrode 22 to provide a spark gap 24, as is well known.

The said electrode 22 has rigidly secured 90 to it a piston 25 of suitable insulating material, which is surrounded by a sleeve of metal 26. The said piston is of such a diameter as to freely slide within the bore 18 and its upper end is flared as at 27 to provide a valve surface adapted to coat with 95 the inclined valve seat 20, above described.

A coiled compression spring 28 is interposed between the upper surface of the said piston 25 and the flange 17 of the insulating member 15 within the enlarged bore 19, 100 and tends to normally force the said piston downwardly, as will be readily apparent.

The lower portion 14 of the insulating member 15 is extended downwardly to provide a depending hollow sleeve 30 which is 105 interposed between the coils of the spring 28 and the central electrode 22, and at the junction of the said sleeve 30 with the lower end 14 of the insulating member 15, there is provided a valve seat 31, adapted to be engaged by a valve member 32, rigid with the said electrode 22.

The upper end of the said electrode 22 extends out of the insulating member 15 for some distance, and is provided with the usual lock nut 33, as well as with the thumb nut 34 for securing the eletric wire or conductor 35 to the said electrode.

In use, the plug is placed in the threaded opening of the cylinder walls of the engine in the customary manner, and upon the suction stroke of the piston the pressure within the bore 18, below the piston 25, will be relieved, thus permitting the spring 28 to force the said piston downwardly until its flared valve 27 seats upon the inclined surface 20 of the shell 10. This downward movement of the piston carries with it the central electrode 22, as well as the small valve 32, thereby unseating the latter.

As the piston moves downwardly, its sides 20 and lower end serves to clean out any carbon which may have been deposited upon the walls of the bore 18, thereby preventing the said carbon from building up within the said bore to such a point that the current 25 will jump from the central electrode to the carbon deposit rather than across the spark gap 24.

Upon the upward stroke of the engine piston, during which the gas within the cylinder is compressed, the pressure will force the piston 25 upwardly against the compression of its spring 28, thereby causing it to reassume the position illustrated in Figure 1. The upward movement of the said piston carries with it the central electrode 22, together with the valve member 32 and causes the latter to engage the valve seat 31, thereby preventing the escape of any of the compressed gas around the cylinder of the 40 central electrode.

In the form of the invention illustrated in Fig. 3, the central electrode 22, instead of sliding within the porcelain insulating member 15, is rigidly held, while the piston 25 is 45 slidably mounted thereon. In this form as well as in the form illustrated in Fig. 1, the said piston is preferably provided with a reduced downward extension 36, which is adapted, when the said piston is in its lower- 50 most position, to surround the lowermost end of the electrode 22 and extend into the spark gap between the electrodes 22 and 23, as is clearly illustrated in Fig. 3. It will thus be seen that both forms not only clean 55 the walls of the bore 18, but also the actual sparking points of the electrodes, 22 and 23.

In some instances where the plugs are used in motors which do not deposit much carbon it is possible to manually control the 60 movements of the piston 25 instead of depending upon the suction and compression within the engine cylinders.

In Figure 4, I have illustrated one means whereby such manual control may be accomplished. The said means comprises a

bracket 40 which may be adjustably secured to the body of the plug by means of a lock nut 41 engaging the threads of the bushing 16. The said bracket 40 has pivoted to its upper end, as at 41, a bell crank lever 42, one arm of which 43 is bifurcated as at 44 to straddle the central electrode 22 and engage the insulating washer 45 with which the said electrode is provided. The other arm 46 of the bell crank lever 42 is pivotally connected, as at 47, to an operating rod 48, which extends to and through the dash 49 of the vehicle and is provided with a suitable handle, 50, whereby it may be moved.

In Figure 4 the parts are shown in their operative positions with the electrode 22 and the piston 25, carried thereby, in their lower or cleaning positions, they having been moved to these positions by sliding the operating rod 48 toward the left, as seen in the said Fig. 4. This movement of the said rod 48 through the bell crank lever connections has forced the electrode 22, together with its piston 25, downwardly, thereby 90 cleaning out the carbon from the bore 18, as was above disclosed. The parts, of course, are restored to their normal positions illustrated in Fig. 1 by moving the rod 48 toward the right, as seen in Fig. 1, 95 which lifts the electrode 22 and the piston 25, as will be readily apparent.

Should it be desired to render the cleaning piston 25 inoperative when using the plug with engines which do not pump oil or deposit large amounts of carbon, it is only necessary to adjust the nuts 33 and 34 upon the electrode 22 until the nut 33 engages the upper surface 51 of the porcelain insulating member 15, thereby drawing the 105 electrode 22 to its uppermost position with its valve 32 engaging the seat 31. When so adjusted it will be apparent that the piston 25 and the electrode 22 cannot descend upon the suction stroke of the engine and the 110 plug may be used in the same manner as the usual stationary electrode plug.

It will be seen that all the forms of this invention provide means whereby fouled spark plugs may be readily and effectively 115 cleaned of the carbon or other deposits thereby eliminating the necessity of removing the plugs from the engine for accomplishing the cleaning.

It is obvious that those skilled in the art 120 may vary the details of construction, as well as the arrangement of parts without departing from the spirit of the invention, therefore it is not wished to be limited to the above disclosure except as may be required 125 by the claims.

What is claimed is:

1. A spark plug for internal combustion engines comprising a shell, one end of which is provided with an electrode; an insulating 130

core member carried by said shell; a central electrode carried by said core member, forming a spark gap with said first mentioned electrode; a piston slidably mounted within 5 said shell surrounding said electrode, adapted to remove deposits of foreign matter from the inner walls of said shell, said piston being provided with a reduced extension adapted to slidably engage said shell carried electrode to clean the same; and a spring within said shell normally urging 10 said piston to said cleaning position.

2. A spark plug for internal combustion engines comprising a shell, one end of which 15 is provided with an electrode; an insulating core member carried by said shell; an integral central electrode slidably mounted in said core member, projecting beyond the ends of said shell and forming a spark gap 20 with said first mentioned electrode; a piston provided with a reduced extension, carried by said central electrode, adapted to clean the inner walls of said shell and said shell carried electrode, said piston being 25 movable in one direction by the pressure of the gases within the engine cylinder; a spring interposed between said core member and said piston, for moving the latter in the opposite direction; and a valve member carried by said central electrode for preventing the escape of the compressed 30 gases from said engine cylinder; and a nut carried by the threaded end of said central electrode, adapted to prevent movement thereof.

venting the escape of the compressed gases from said cylinder.

3. A spark plug for internal combustion engines comprising a shell, one end of which is provided with an electrode; an insulating core member provided with a valve seat, carried by said shell; an integral central electrode slidably mounted in said core member with its ends projecting beyond the ends of said shell, one of them being threaded, and the other forming a spark gap with said first mentioned electrode; a piston provided with a reduced extension, carried by said central electrode, adapted to clean deposits of foreign matter from the inner walls of said shell, and from said shell carried electrode, said piston being movable in one direction by the pressure of the gases within the engine cylinder; a spring interposed between said core member and said piston, for moving the latter in the opposite direction; a valve member carried by said central electrode for engagement with said valve seat for preventing the escape of the compressed gases from said engine cylinder; and a nut carried by the threaded end of said central electrode, adapted to prevent movement thereof. 50

In testimony whereof I affix my signature.
GEORGE SEIBERT, JR.
